Maximilian H. Kern, Inventor:
by Frank P. Nuttsworth, his Atty.

UNITED STATES PATENT OFFICE.

MAXIMILIAN H. KERN, OF NEW YORK, N. Y., ASSIGNOR TO ROBERTS NUMBERING MACHINE COMPANY, A CORPORATION OF NEW YORK.

NUMBERING-HEAD.

1,385,835.

Specification of Letters Patent. Patented July 26, 1921.

Application filed November 6, 1920. Serial No. 422,237.

To all whom it may concern:

Be it known that I, MAXIMILIAN H. KERN, a citizen of the United States, residing at Ridgewood, in the borough of Queens, city 5 of New York, county of Queens, and State of New York, have invented certain new and useful Improvements in Numbering-Heads, of which the following is a specification, reference being had therein to the accompanying drawings, which form a part thereof.

My invention relates to numbering heads, and more particularly to the detent pawl structure of such heads, which structure is 15 applicable to either automatic or non-automatic wheel printing machines.

In numbering heads and other types of wheel printing machines, a plurality of rotatably mounted wheels having printing 20 characters or types upon the periphery thereof are employed, such wheels being progressively and automatically rotated with the actuation of the machine in some types of heads, and being hand-operated in 25 other types of heads.

The printing surfaces of the various wheels are inked between impressions in different manners according to the structure of the machine as determined by its partic- 30ular character of use.

These characteristics of the machine are old and well known in this art, my invention relating more particularly to the particular construction of the detent pawl mechanism by which the springs acting upon the pawl associated with each wheel, will have a tensioning pressure applied thereto which will be uniform with the tensioning pressure applied to the pawls of all other wheels, and 40 whereby the vibration resulting from the actuation of the mechanism will have no tendency to break the detent pawl springs or cause a variance in the tension thereof which will tend to permit one of the wheels 45 to rotate more freely than other wheels, with a resultant likelihood of rotary movement of one wheel being imparted to the adjoining wheels through the frictional engagement of said wheels, or the presence of 50 congealed or dried ink between adjacent wheels.

In addition to having the above characteristic of maintaining a substantially constant uniform tension in the detent pawl springs, 55 a numbering head made in accordance with

my invention may be quickly and accurately assembled or disassembled, and the number of parts entering into the machine may be reduced.

The invention consists primarily in a 60 numbering head embodying therein a frame, a plurality of printing wheels rotatably mounted in said frame, each of said wheels having a ratchet wheel rotatable therewith, a detent pawl coöperating with each ratchet 65 wheel, a spring having one end thereof supported upon said frame and the other end thereof engaging a pawl, and means coöperating with said frame and applying a constant tensioning pressure to said spring intermediate said point of support and said point of engagement thereof with the pawl; and in such other novel features of construction and combination of parts as are hereinafter set forth and described, and more 70 particularly pointed out in the claims here- 75 to appended.

Referring to the drawings, Figure 1 is a rear view of a numbering head embodying my invention;

Fig. 2 is a section thereof on the line 2—2 of Fig. 1; and

Fig. 3 is a detail isometric view of the form of the pawl detent springs shown in Fig. 1.

Like letters refer to like parts throughout the several views.

In the accompanying drawings, I have shown my invention as applied to the head of a hand-operated numbering machine, although it is apparent that it is equally applicable to numbering heads to be applied to power operated machines, or to machines in which the various printing wheels are manually operative instead of being automatically actuated as in the two types of wheels above referred to. All types of wheel printing machines have certain characteristics in common which are exemplified in the machine shown in the drawings.

In the form of the invention shown in the drawings, I employ a yoke frame *a* having therein a fixed shaft *b* upon which a plurality of wheels *c*, *d*, *e*, *f*, *g* and *h* are rotatably mounted. Each printing wheel *c* to 105 *h* carries a ratchet wheel *c'*, *d'*, *e'*, *f'*, *g'* and *h'* secured thereto or otherwise associated therewith, so as to control the rotary movement of said wheel in one direction through the spring pressed pawls *c*², *d*², *e*², *f*², *g*² and 110

h^2 associated therewith respectively. Said pawls also serve to insure accurate alignment of the characters on said wheels which are in the printing position.

5 In the form of the invention shown, I employ a ratchet wheel i having associated therewith a pawl i' , the function of said ratchet wheel being to permit the setting of the head in a manner to cause a repetition 10 of the printing of a definite number, a construction known in the art as a repeat mechanism.

In the form of the invention shown, the digit wheels c to h are progressively and 15 automatically actuated by means of a swing frame j carrying a sequence of graduated pawls k , spring pressed in the usual manner into engagement with the various ratchet wheels c' to h' , each of said wheels being 20 provided with a recess such as that shown at l Fig. 2, for permitting said pawl k to progressively engage the ratchet teeth of succeeding wheels.

The construction heretofore described is 25 old and well known in this art, and no claim of invention is made thereto, my present invention relating more particularly to the manner of applying spring pressure to the various pawls c^2 to h^2 and to the pawl i' 30 coöperating with the repeat wheel i when such wheel is used in the mechanism of the head, although such is non-essential, and is employed only in some types of hand-operated automatic machines.

35 Heretofore in this art, the detent pawls have been pressed into engagement with their coöperating ratchet wheels by various types of springs. Wire springs have been employed secured by means of a coil section upon the shaft upon which the pawls are pivoted, and there have also been used comb springs secured to the yoke in which the printing wheels are mounted, by means of a plurality of screws.

45 In the former construction the labor of assembling the pawls of the machine is somewhat great, while in the latter type of machine there is a tendency of the head of the comb spring to bow slightly between the 50 points of the application of the screws and thus cause the development of an unequal tensioning pressure upon different pawls. There is also likelihood of said screws becoming loosened as a result of vibration, 55 with a resultant loss of tension in the spring and increased likelihood of a failure of the printing wheels to work properly.

In a numbering head made in accordance with my invention, I employ a spring m of 60 the comb type, the teeth of which adjacent the free ends are adapted to bear upon the respective pawls and the head of which is adapted to be supported in a fixed relation to the top of the yoke a .

65 This spring is tensioned through the me-

dium of a member rigidly supported with relation to said yoke and applying a tensioning pressure to said spring intermediate the point of support thereof upon the yoke, and of the engagement of the several 70 teeth with their coöperating pawls. In this manner, I am not only enabled to accurately position each spring tooth with relation to its pawl, but apply and maintain a uniform tensioning stress throughout the entire 75 breadth of the comb spring, and thus insure the development of substantially the same tension in each tooth with a resultant uniformity in the pressure exerted by each pawl upon its coöperating ratchet.

In the drawings I have shown the spring m as having a sequence of teeth m' , m^2 , m^3 , m^4 , m^5 and m^6 associated with the pawls c' to h' respectively, and a tooth m^7 associated with the pawl i' . The head n of this 80 comb spring m is formed to provide a transverse pocket or trough n' adapted to receive the edge of the top bar of the frame a , and a second pocket or trough n^2 , the mouth of which is presented in the reverse direction, 85 the loop of metal forming said pocket n^2 having its edges in close proximity to the arms of the yoke a . The side of said pocket n^2 adjacent the teeth m' to m^7 is deeper than that adjacent the pocket n' , so as to 90 offset said teeth in relation to said pocket n' , or to the top of the yoke a .

The various spring teeth m' to m^7 are tensioned by means of a pin o passing through openings in the arms of the frame 100 a and through the pocket n^2 and engaging the bottom of said pocket, it being necessary to tension the various springs by applying a pressure thereto toward the yoke a in 105 order to permit the insertion of said pin o , after which a constant tension of the springs will be maintained by said pin which will engage every point of the head of the comb spring and thus insure uniformity in the 110 tensioning pressure upon said springs.

In assembling a head made in accordance with my invention, after the wheels and the other mechanisms associated therewith have been mounted in the yoke a , and the 115 various pawls properly mounted and engaged each with its coöperating ratchet wheel, the pocket or trough n' of the spring plate m is placed with its walls astride the edge of the top of the yoke a , thus bringing the side edges of the trough n^2 between the 120 arms of said yoke and accurately positioning each of the teeth m' to m^7 with relation to the pawl against which it is to bear. In this manner any subsequent displacement of the spring teeth is prevented, no adjustments 125 being required to assure the proper relation of the teeth with the coöperating pawls, this being determined when forming said teeth and when positioning the comb with relation to said yoke.

When the spring is in this position, a tensioning pressure is applied thereto intermediate the point of engagement of the troughed portion n' with the yoke a and 5 of the several teeth with their coöperating pawls. This forces the troughed portion n^2 inwardly of the yoke so as to permit the pin o to be inserted in the opening in the arms of said yoke and passed lengthwise 10 through said troughed portion n^2 .

When the pin is properly positioned, the tensioning pressure is relieved, the tension thus developed in the teeth m' to m^2 forcing the bottom of the troughed portion n^2 into 15 engagement with said pin, the reflex action of said teeth being very slight, so that the engagement of the bottom of the trough with the pin will maintain all of said teeth under tension. Since the entire spring n 20 flexes as a whole, and since the pin o is engaged with the bottom of the trough throughout the entire length thereof, it is apparent that there will be uniform tension upon all of the teeth which will be constant 25 since there can be no displacement of the pin o and no tendency of said spring to bow by reason of the transverse rigidity imparted thereto by the troughed portion n' and n^2 .

30 It will be observed that in assembling the head, all of the springs coöperating with the various pawls are simultaneously applied to the head and are held in position before said springs are placed under tension.

35 The insertion of the pin o does not require any drilling and tapping of the yoke a . Said pin, when the spring has been properly tensioned by means of a suitable tool or jig, may be quickly assembled in the machine, or 40 as quickly removed therefrom when it is desired to disassemble the head.

When a spring construction such as is herein described, is employed, all of the spring teeth will be simultaneously and uniformly tensioned and no such loss of adjustment of parts can occur while the machine is in use, as to prevent loss of tension of the springs. The manner of mounting the spring permits the use of fairly heavy 50 springs, thus imparting a greater factor of safety in the operation of the head and insuring a more accurate alinement of the characters in the printing position, since in the event of slight overrunning of any wheel, 55 the detent pawls are relied upon to return any wheel to its proper alined position.

It is apparent that the construction herein described is applicable to various different types of numbering heads, either hand 60 or machine operated, and that various modifications in the construction of the spring plate m and in the manner of maintaining the tension of this plate through the medium of a pin engaging the spring plate throughout the entire width thereof, may be em-

ployed, varying with changes of design of the head structure proper.

It is therefore not my intention to limit the invention to the precise details of construction shown in the drawings, it being 70 apparent that such may be varied without departing from the spirit and scope of the invention.

Having described the invention, what I claim as new and desire to have protected by 75 Letters Patent, is:—

1. A numbering head embodying therein a frame, a plurality of printing wheels rotatably mounted in said frame, each of said wheels having a ratchet wheel rotatable 80 therewith, a detent pawl coöperating with each ratchet wheel, a spring having one end thereof supported upon said frame and the other end thereof engaging a pawl, and means coöperating with said frame and applying a constant tensioning pressure to said spring intermediate said point of support and said point of engagement thereof with the pawl.

2. A numbering head embodying therein 90 a yoke frame, a plurality of printing wheels rotatably mounted therein, a ratchet wheel carried by and rotatable with each printing wheel, a detent pawl coöperating with each ratchet wheel, a comb spring each tooth of 95 which coöperates with a detent pawl, the free edge of the head of said comb spring being formed to engage the edge of the cross bar of said yoke frame, and other portions thereof being adapted to engage the arms of 100 said frame, and means coöperating with said frame and applying a constant tensioning pressure to said spring intermediate said point of support and said point of engagement thereof with the pawl.

3. A numbering head embodying therein 105 a yoke frame, a plurality of printing wheels rotatably mounted therein, a ratchet wheel carried by and rotatable with each printing wheel, a detent pawl coöperating with each 110 ratchet wheel, a comb spring each tooth of which coöperates with a detent pawl, the free edge of the head of said comb spring being formed to engage the edge of the cross bar of said yoke frame, and other portions 115 thereof being adapted to engage the arms of said frame, and a member removably mounted in said yoke frame and adapted to engage said spring throughout its entire width intermediate said formed portion of the head 120 engaging the frame and the points of engagement of the several teeth with their respective detent pawls, whereby a constant uniform tensioning pressure is applied to all 125 of said teeth.

4. A numbering head embodying therein 130 a yoke frame, a plurality of printing wheels rotatably mounted therein, a ratchet wheel carried by and rotatable with each printing wheel, a detent pawl coöperating with each

ratchet wheel, a comb spring each tooth of which coöperates with a detent pawl, the head of said spring having a transverse pocket adapted to receive the cross bar of the yoke frame and a relatively deeper pocket opening outwardly of said frame, the loop of metal forming said pocket having its side edges in close proximity to the sides of said frame and being positioned adjacent the several teeth, and a pin passing through openings in the sides of said frame, and said last named pocket in continuous engagement

with the bottom thereof, whereby a continuous, uniform tensioning pressure is applied to all of said teeth.

15

In witness whereof I have hereunto affixed my signature, in the presence of two subscribing witnesses, this 24th day of September, 1920.

MAXIMILIAN H. KERN.
